UNITED STATES PATENT OFFICE.

CASPER MUELLER, OF BOSTON, MASSACHUSETTS.

OIL-FEEDER.

SPECIFICATION forming part of Letters Patent No. 434,113, dated August 12, 1890.

Application filed April 29, 1890. Serial No. 349,921. (No model.)

To all whom it may concern:

Be it known that I, CASPER MUELLER, of Boston, county of Suffolk, State of Massachusetts, have invented an Improvement in Oil-Feeders, of which the following description, in connection with the accompanying drawings, is a specification, like letters and figures on the drawings representing like parts.

This invention relates to oil-feeders for engines, and has for its object to provide an oil-feeder of novel construction, as will be hereinafter pointed out in the claims at the end of this specification.

Figure 1 is a vertical longitudinal section of an oil-feeder embodying my invention; Fig. 2, a detail in side elevation of the lower portion of the feeder shown in Fig. 1, looking toward the left in said figure; Fig. 3, a detail of the regulator, and Fig. 4 a sectional detail on line xx , Fig. 2.

The oil-receiving chamber or receptacle of the feeder is herein shown as a globe A, preferably of glass. The globe A is provided with substantially diametrically opposite openings, normally closed by covers a' , the cover a' being herein shown as provided with an annular groove a^2 in its upper face to receive an annular flange a^3 on the globe A. The cover a' has on its upper side an annular flange or tubular extension a^4 , provided, as herein shown, with screw-threads on its inner and outer sides. The tubular extension a^4 is engaged on its inner side with a sleeve or tube a^5 extended up through the opening in the top of the globe A and outside of the said globe. The said sleeve or tube has screwed into it a hollow regulating-plug b, having its lower portion made plain and provided with a cam-shaped slot b' , provided, as herein shown, at its highest point (see Fig. 3) with a notch b^2 , adapted to receive a pin or projection b^3 on a spindle b^4 extended through the hollow plug b and sleeve a^5 , the said spindle preferably having its lower end made conical or pointed to fit a conically-shaped seat and close the outlet-opening b^5 for the globe A, the said opening being preferably formed in an independent nozzle b^6 secured to the under side of the cover a' . The spindle b^4 below the end of the hollow plug b is encircled by a spiral spring b^7 , one end of which abuts against the said hollow plug and the other

end against a pin b^8 extended through the spindle, but it may be a collar on said spindle. The spring b^7 acts to force the spindle b^4 down toward its seat at all times. The outlet-nozzle b^6 for the globe A is extended into a chamber c, having two of its opposite sides preferably cast integral with the cover a' , and with a discharge-nozzle c' forming the bottom of the chamber c. The two opposite sides of the chamber c are made of glass or other transparent material, the said sides forming sight-windows c^3 , which are removable, but are normally locked in place by the thumbscrew c^5 , pivoted on one side of the chamber c, and having arms which lap over or extend beyond the edge of the said side and fasten the removable windows in place, the rear edge of the said windows abutting against the projecting edges c^x of the opposite side, as clearly shown in Fig. 4. The windows c^3 may be readily removed by turning the thumbscrew substantially at right angles to the position shown in Fig. 4. The hollow tube a^5 is provided with suitable feed-holes 2, through which oil in the globe may pass into the said tube. The hollow plug constitutes a regulator to determine the quantity of oil to be fed to the bearing to be oiled, and this plug in practice will be screwed down into the tube a^5 more or less, and will be fastened in adjusted position by a set-screw 3. The further the said plug is screwed down the less the feed. When the feed is to be stopped altogether, the spindle b^4 will be turned in a direction to permit it to descend under the action of spring b^7 and close the outlet b^5 , as in Fig. 1.

To enable a stream of oil to be fed, lift the spindle and rotate it partially until the pin b^3 enters the notch b^2 , as in Fig. 3, and a sufficient quantity of oil having been discharged, the spindle will be further turned to place the pin b^3 in the regular feed-notch 4, (herein shown as the end of the groove b' at the left in Fig. 3,) the spindle in this last position permitting the oil to be delivered in regulated quantity.

The sight-windows may be easily removed to be cleaned by turning the thumbscrew.

I claim—

1. In an oil-feeder, the globe, the covers a' , the delivery-tube b^5 , the tube a^5 , the spin-

- die having a pin b^3 and a spring to normally depress the said spindle, combined with the hollow regulating-plug, having a cam-slot entered by the said pin, the said cam-slot having two notches to be entered by the said pin, one notch to insure the discharge of oil in regulated quantity and the other to enable a stream to be discharged, substantially as described.
- 10 2. In an oil-feeder, the chamber c , having open sides and sight-windows c^3 to close the same, combined with the thumb-screw c^5 , hav-

ing arms to overlap the edges of and keep the sight-windows in place, the said windows abutting against the projecting edges of the 15 opposite side, substantially as described.

In testimony whereof I have signed my name to this specification in the presence of two subscribing witnesses.

CASPER MUELLER.
